UNITED STATES PATENT OFFICE.

JOHN BRANDWOOD AND JOSEPH BRANDWOOD, OF BURY, ENGLAND.

METHOD OF AND APPARATUS FOR TREATING YARN.

Application filed July 12, 1922. Serial No. 574,498.

To all whom it may concern:

Be it known that we, JOHN BRANDWOOD and JOSEPH BRANDWOOD, subjects of the King of Great Britain and Ireland, residing 5 at Bury, in the county of Lancaster, England, have invented certain new and useful Improvements in Methods of and Apparatus for Treating Yarn, of which the following is a full, clear, and exact description.

10 Our invention relates particularly to the art of drying yarn which is bleached or dyed on a beam, such for instance as disclosed in our prior Patent No. 1,211,068, and includes both a method of and apparatus for drying 15 the yarn.

Beams of this character usually contain from 300 to 500 individual ends or threads, and it is customary to size and dry the 20 yarn after the dyeing or bleaching operation in the open width or sheet by winding the yarn off one or more beams over cylinders or through drying chambers, and then rewinding the yarn either on one or more beams or on bobbins, quills or the like. This method 25 is satisfactory where the yarn is to be put on a weaver's beam for the warp of the loom, since in that case the yarn is drawn simultaneously from a number of beams, and consequently the sheet passing through 30 the drying operation contains in the aggregate a large number of threads and is therefore sufficiently strong to withstand the strains to which it is subjected. If for instance each beam should be 54 inches long 35 and should contain 432 individual threads and yarn should be dried simultaneously from 10 beams, the sheet from each beam would have 8 threads to the inch but the composite sheet from the 10 beams would 40 have 80 threads to the inch which would afford sufficient tensile strength to permit of the necessary pull being exerted on the sheet to dry, size and rewind it without 45 breakage.

This method, however, is not practical where the yarn is to be used for quilling, i. e., for the filling or weft of the loom. For that purpose each individual thread is separated and wound on a quill or bobbin 50 by a quilling machine, and it is not possible, at least with any quilling machines in common use, to quill more than three or four hundred threads simultaneously. Therefore yarn from only one beam at a time can 55 be sized, dried and quilled, and the sheet

in its open width from the single beam as it passes through the drying operation is so tenuous and fragile that there is much breakage of the yarn, making the operation slow and expensive. It is manifest that the 60 same problem is present where only a small quantity of warp yarn is required and therefore yarn from only one or two dye beams is to be dried and beamed.

Various methods have heretofore been 65 proposed for overcoming this difficulty, such, for instance, as quilling the yarn while wet and subsequently drying it on the quills, but all of these have proved to be slow and expensive and otherwise unsatisfactory.

An object of our invention is to provide a method and apparatus for overcoming these difficulties which will enable the drying to be done very rapidly and cheaply and 75 will relieve the yarn of strain and eliminate breakage of the yarn, while delivering the yarn in the most convenient form for quilling or rebeaming.

In accordance with our invention we contract the yarn as it comes off from the dye beam and before drying into a compact or narrow band or belt having as much strength per unit of width as has the wide sheet composed of the yarn from several 80 beams which is to be used for the warp of the loom. This enables the yarn from a single dye beam to be expeditiously dried without risk of breakage and at a minimum 85 of cost.

In the drying operation the yarn is usually run over heated cylinders known as drying cans which are usually of substantially the same width as the dye beams in order 90 to accommodate a full width uncontracted sheet of yarn. In order to utilize the full width of the surface of the drying cans our method contemplates passing the contracted band of yarn in a spiral or serpentine manner over the drying cans. Preferably it 95 passes in an opposite direction over the successive cans so as to bring its two sides alternately toward the heated surface and facilitating quick and even drying.

If two cylinders are used they will be 100 driven in opposite directions, and suitable guides will be provided to cause the coils to travel longitudinally of the cans as rapidly as they are being unwound from one 105 and wound on the other end of the cans. 110

For contracting the sheet of yarn into the narrow band, a suitable eye or guide of proper width may be employed, or for the finer numbers of yarn an expansion comb of usual construction may be used.

After drying, the yarn may be delivered to a folding mechanism of any standard type and folded and stored away ready for quilling if required for filling, or it may be re-
10 expanded and rebeamed on to a section beam in a single sheet or in sectional sheets.

An advantage of our method and apparatus is the fact that the yarn from two dye beams may be treated at one time, the two
15 bands being spirally wound from opposite ends of the drying cans to the middle without interference. Our invention has other objects and advantages, and includes other features and details of construction, as will
20 hereinafter more fully appear. We will now describe the operation of our improved method with the aid of the illustrated apparatus and will thereafter point out our invention in claims.

25 Fig. 1 is a side elevation of an apparatus adapted for carrying out our method;

Fig. 2 is a plan of the same;

Fig. 3 is a rear end elevation of the same;

30 Fig. 4 is a sectional detail of the folding mechanism taken on line 4—4 of Figure 3;

Fig. 5 is a plan of a warping machine adapted to reexpand and rebeam the dried yarn in accordance with our method.

In the illustrated apparatus, yarn from
35 two dye beams, 1 and 2, is shown as being simultaneously dried. Before passing through the drying operation, such as running through a drying cylinder or running over or around drying cylinders, the yarn is
40 contracted from the full width sheet into the narrow bands *e* and *f*, respectively. In the construction shown, the yarn from the beam 1 is run through a suitable narrow guide, such as a porcelain eye 3, in order to contract it into band *e*, while the same result
45 is effected with the yarn from the beam 2 by running it through an expansion comb 4 of usual construction. As above stated, the eye 3 will be employed except for the fine numbers of yarn with which the expansion
50 comb may more advantageously be used.

From the guides 3 and 4, the yarn is wound spirally or in serpentine fashion over and around one or more drying cans or cylinders. In the illustrated construction there are two such drying cans 5 and 6 disposed in the same horizontal plane and both having their bearings supported on suitable frames or standards 7 and 8. These drying cans are positively driven in opposite directions, as indicated by arrows. As shown, a belt 9, driven from any suitable source of power, drives a pulley 10 on one end of the shaft for the drying can 6, and the two drying cans are geared together by gear wheels
60

11 and 12 on the cans 5 and 6, respectively. The drying cans are heated in any usual or suitable manner, as by steam entering through pipe 13, the branches of which pass through the hollow bearings of the drying cans.

To guide the coils of the yarn along the drying cans 5 and 6, suitable guides, such as porcelain eyes 14 are provided in a vertically disposed board 15 supported between the cans 5 and 6 by brackets from the frame elements 7 and 8.

In the arrangement shown in the drawings, the two bands of yarn *e* and *f* are wound, respectively, from the left and right ends of the drying cans to their center, whence they pass to a suitable folding mechanism or to an expanding device and thence to a warping machine for rebeaming. The two contracted bands *e* and *f* pass from their guides 3 and 4 preferably over a roller as shown and thence underneath the first drying can 5 and thence rearwardly through the first eyes 14 and over the drying can 6 in the opposite direction, and thence forwardly through the second eyes 14 and thence over the drying can 5, and so on, until the middle of the drying cans is reached. In this manner it will be observed that the two sides of the bands are alternately brought in contact with the drying surfaces, and the parts are so designed that the travel of the yarn in this serpentine path will be sufficient to cause it to be completely dried.

In the construction shown in Figures 1 to
4, the yarn passes from the drying cans to a folder or plaiter by which it may be folded in a bag or wrapper and stored away readily for quilling, although it is manifest that it may pass to a quilling machine immediately from the drying operation. The folding mechanism is also positively driven from the pulley 10. It consists of an oscillatory hanger having two side members 16 and 17 connected at their bottom by a rod 18 and pivoted at their upper ends on a shaft 19 which bears in the ends of horizontal arms 20 and 21, bolted at their inner ends to the frame members 7 and 8, respectively.

The shaft 19 has on its end adjacent the arm 20 a pulley 22, and a pulley 23 is fixed on the shaft of the drying can 6 just inside the pulley 10 and is connected to pulley 22 by belt 24. In this manner continuous rotation is imparted to the shaft 19. Also the hanger is oscillated by the crank and pitman construction illustrated on the opposite side of the machine. A pulley 25 on the end of shaft 19 is connected by belt 26 to a pulley 27 the shaft of which bears in arm 21 and has on its inner end a crank disc 28 carrying an adjustable crank 29 which crank is connected by pitman 30 to side member 17 of the hanger.

The shaft 19 is provided at its center

with two pulleys 31 and 32 fixed on the shaft, and in the lower ends of the oscillatory arms 16 and 17 bears a transverse shaft 33 parallel to the shaft 19 which has fixed to its middle portion two pulleys 34 and 35 directly underneath the pulleys 31 and 32, and which is driven by a belt 44 which passes over pulley 45 in shaft 19 and over pulley 46 on shaft 33. The two shafts 19 and 33 are connected by two braces 36 and 37 disposed just outside the two pairs of pulleys, and these braces are provided with vertically elongated slots immediately above the pulleys 34 and 35 in which bear two idler rollers 38 and 39 resting by gravity upon the pulleys 34 and 35.

In the operation of the folder, the bands *c* and *f* are passed over the pulleys 31 and 32 and thence brought inwardly around the rollers 38 and 39 and passed between these rollers and the pulleys 34 and 35. It is apparent that as the apparatus is driven, the folding frame will be oscillated and the yarn laid in folds of determined length in the usual way.

The relative rate of movement of the positively driven drying cans and of the folding mechanism is such that the yarn is fed to the folding mechanism just as fast as it is required without any undue strain upon the yarn at any point, and the folding motion will preferably lead just sufficiently to keep the yarn taut.

If the yarn is required in small quantities for warp yarns, it may be taken through an expanding comb after leaving the dryer and run back to the section beam in the manner illustrated in Figure 5. After the drying operation, the band *c*, for instance, may pass through an eyelet 40 and thence be brought back to its original width and fed to a warping machine. This machine is of the usual type, but will be positively driven and provided with friction or cone speed regulation in order that the speed of the warper may be varied at will by the operator. From the porcelain eye 40, the dry yarn passes over a warper 41 of well known design and thence through an expansion comb 42 on to the section beams 43. The section beam is made by mounting wooden blocks of the required length and this section beam is positively driven in the warper. In between each wooden block is mounted a thin metal disk of suitable diameter in order to insure the thorough separation of threads of each section and cause each section to be built up independently.

It will be understood that after the yarn is dried and rebeamed in this manner, the sections can be drawn off the rod, the disks removed, and each section of yarn will remain firm and solid, and will not collapse, and the threads will not become disarranged

or get out of place. They will then be put behind a sizing frame mounted on a square rod, and several colors may be mounted on this rod in the order required on the weaver's beam in order to make the necessary pattern. The outsides of the two end sections will be protected by metal disks, and the sections will be screwed up tightly so that they again form one solid beam made of various colors ready for running through the sizing frame along with other beams of grey, bleached or colored yarn, all to be sized and run to pattern on the weaver's beams.

It is obvious that our invention is in no wise limited to the exact construction of apparatus illustrated and above particularly described, but that various changes therein will readily suggest themselves to any one skilled in the art without departing from the spirit or scope of our invention.

We claim:

1. The method of drying yarn which consists in drawing it in sheet form from a perforated beam or the like on which it has been subjected to wet treatment, and contracting the sheet so drawn into a narrow band, the force applied for the withdrawal of the yarn direct from the beam serving also to draw the narrow band simultaneously through a drying medium.

2. The method of drying yarn contained in a wet state on a beam or the like consisting in withdrawing the yarn in a sheet from the beam and contracting the sheet into a narrow band and then drawing the band in spiral form over a heated cylinder until dry.

3. The method of drying yarn contained in a wet state on a beam or the like consisting in withdrawing the yarn in a sheet from the beam and contracting the sheet into a narrow band and then drawing the band contiguous to two heated surfaces with its opposite sides alternately toward the two surfaces.

4. The method of drying yarn contained in a wet state on a beam or the like consisting in withdrawing the yarn in a sheet from the beam and contracting the sheet into a narrow band and then drawing the band over two drying cans with one side of the band engaging the surface of one can and the other side engaging the surface of the other can.

5. The method of drying yarn contained in a wet state on a beam or the like consisting in passing the sheet of yarn from the beam through a contracting member and passing the band thus formed spirally and oppositely over two oppositely rotating drying cans.

6. An apparatus for the treatment of yarn comprising, in combination with a holder for a dye beam or the like, a drying

mechanism including a power driven device adapted to exert a pull on yarn withdrawn from a beam in said holder, and a relatively narrow guide for the yarn in advance of said mechanism.

7. An apparatus for the treatment of yarn comprising, in combination with a holder for a dye beam or the like, a rotative drying can disposed adjacent said holder, and a relatively narrow guide for the yarn in advance of said can.

8. An apparatus for the treatment of yarn comprising, in combination with a holder for a dye beam or the like, two power-driven, oppositely rotative drying cans adjacent said holder, and a relatively narrow guide for the yarn in advance of said cans.

9. An apparatus for the treatment of yarn comprising, in combination with a holder for a dye beam or the like, two power-driven, oppositely rotative drying cans adjacent said holder, a relatively narrow guide for the yarn in advance of said cans, and a plurality of guides for the yarn disposed between the

two cans at intervals along the length 25 thereof.

10. An apparatus for the treatment of yarn comprising, in combination with a holder for a dye beam or the like, a rotative drying can disposed adjacent said 30 holder, a relatively narrow guide for the yarn in advance of said can and means after said can for disposing of the dried yarn.

11. An apparatus for the treatment of yarn comprising, in combination with a 35 holder for a dye beam or the like, two power-driven, oppositely rotative drying cans adjacent said holder, a relatively narrow guide for the yarn in advance of said cans, a plurality of guides for the yarn disposed between the two cans at intervals along the length thereof, and means after said cans and driven in conjunction therewith for disposing of said dried yarn.

In witness whereof, we hereunto subscribe 45 our signatures.

JOHN BRANDWOOD.
JOSEPH BRANDWOOD.
